UNITED STATES PATENT OFFICE.

MICHAEL O'ROURKE, OF PHILADELPHIA, PENNSYLVANIA.

STREET-PAVEMENT.

SPECIFICATION forming part of Letters Patent No. 340,893, dated April 27, 1886.

Application filed September 14, 1885. Serial No. 177,031. (No model.)

To all whom it may concern:

Be it known that I, MICHAEL O'ROURKE, a citizen of the United States, residing in Philadelphia, Pennsylvania, have invented certain 5 Improvements in Street-Pavements, of which the following is a specification.

The object of my invention is to produce a strong and durable pavement for streets; and my invention consists in the combination and 10 arrangement of materials hereinafter particularly specified, the figure in the accompanying drawing showing a transverse section of my improved pavement.

The Belgian block pavement is generally 15 considered to be the best and most durable which can be employed, especially where the traffic is heavy; but heretofore it has been customary to lay these pavements upon a simple bed of gravel, usually about fifteen 20 inches, or thereabout, in depth, and as a bed of this character is apt to be more yielding in some places than in others, the consequence is that, however carefully the blocks may be laid and rammed, traffic upon the pavement 25 soon causes a sinking of parts and numerous irregularities of surface, requiring frequent repairs.

The primary object of my invention is to remedy this defect of the Belgian pavement 30 by providing for the blocks a foundation of even firmness and consistency throughout; and to this end, in place of the usual gravel bed, I employ a foundation prepared in the following manner: I take a quantity of the 35 cement known as "Anchor Cement," and mix therewith a quantity of the "breaker-dust" resulting from the breaking of hard stone in a "Blake" or other crusher, and a quantity of hard broken stone, the largest pieces of 40 which do not measure more than an inch and a half in any direction, and a quantity of like stone the largest pieces of which do not measure more than two inches in any direction. The proportions in which I prefer to mix 45 these materials are: to two and a half parts, by measurement, of the cement five parts of the breaker-dust, four parts of the inch-and-a-half broken stone, and seven parts of the two-inch broken stone, and with these materials I 50 use a quantity of water, to make the mixture

plastic, and allow it to be laid while in that condition to the depth of seven inches, or thereabout, upon the bed of the street. This foundation A is rammed in order to compact it and cause it to present an even surface. 55 Upon this foundation, when dry, I lay a quantity of clean bar-sand or sharp gravel, or a mixture of the two, to a depth of from two to two and a half inches, as shown at B. Upon the bed thus prepared I place the granite Belgian blocks D, these blocks being preferably eight to twelve inches long by three and a half to four and a half or five inches wide and seven to eight inches deep. The interstices between the blocks I fill with small stones of 65 suitable size for the purpose, and can utilize the small particles of broken stone screened from that used in preparing the bed hereinabove described. The blocks I then ram until the desired compactness and even surface 70 have been attained, and then pour into the interstices between the blocks a quantity of roofing pitch composition or other coal-tar product.

It should be understood that I do not wish 75 to limit myself to the exact ingredients which I have specified as composing the foundation of my improved pavement, nor to the exact proportions of ingredients described, as these may be varied without departing from the essential feature of my invention, which is the providing of a Belgian block pavement with a foundation in the nature of an artificial stone which will present uniform resistance at all 80 parts, and thus prevent sinking of portions of 85 the pavement under heavy traffic.

The foundation of my improved pavement presents, in effect, a rigid and homogeneous artificial-stone arch extending from curb to curb, so that strains upon any one portion of 90 said arch are transmitted to other portions of the same; and in this respect my invention differs, essentially, from a pavement having a foundation or bed of simple broken stone, which, even if well laid, is not a rigid and 95 homogeneous foundation.

I claim as my invention—

1. A Belgian block pavement in which the granite blocks composing the surface of the pavement are combined with a foundation of 100

artificial stone or cement, forming a rigid and homogeneous bed, all substantially as and for the purpose set forth.

2. The combination of the granite surfacing-blocks, the sand or gravel bed, and the foundation of cement and broken stone, forming a rigid and homogeneous support for the pavement, all substantially as specified.

In testimony whereof I have signed my name to this specification in the presence of two subscribing witnesses.

MICHAEL O'ROURKE.
